UNITED STATES PATENT OFFICE.

HERMIE CLARENCE NEGGESMITH, OF NEW YORK, N. Y.

COLLAR CLASP.

Application filed April 15, 1921. Serial No. 461,488.

To all whom it may concern:

Be it known that I, HERMIE CLARENCE NEGGESMITH, a citizen of the United States of America, residing in the borough of Bronx, county of Bronx, city and State of New York, have invented certain new and useful Improvements in Collar Clasps, of which the following is a specification.

This invention relates to clasps for the 10 lapels of soft collars, or the like, and aims to provide improvements therein.

The invention provides a collar clasp, which can be applied to the collar without straining the fabric, and thereby without 15 destroying or impairing the finish and neat appearance of the collar. It further provides a clasp, capable of being applied by a simple and convenient manipulation.

The invention further provides a clasp 20 which will firmly and securely hold the lapels of the collar without piercing or perforating the fabric, so as not to impair the life or appearance of the collar.

The invention further provides a device 25 of simple and durable mechanical construction, of pleasing appearance, and adapted for the adjunction or combination of ornamental devices.

An embodiment of the invention is illustrated in the accompanying drawings, 30 wherein:

Figure 1 is a front view of said embodiment applied to a soft collar.

Fig. 2 is a longitudinal sectional view 35 thereof, with the arms in open position.

Fig. 3 is a sectional view, on the line III—III, Fig. 2; and

Fig. 4 is a sectional view, on the line IV—IV, Fig. 2.

Referring to said drawings, numeral 10 designates a bar, adapted to lie beneath the fabric, the edges of which are to be held together, and 12, 12 designate arms, pivoted or hinged at their adjacent ends to said 40 bar, as indicated at 13, and adapted to overlie the fabric, the edges of which are to be held.

The arms 12, 12, at their free ends 15, and the ends of the bar 10, are provided with 45 coacting means 17 for gripping the fabric without piercing or perforating it. The gripping means 17 preferably comprise blunt pins 19, conveniently located on the bar 10, and sockets 20, conveniently located 50 on the free ends 15 of said arms 12.

The free ends of the arms 12 are preferably provided with buttons or knobs 22, preferably of an ornamental character, or capable of having an ornamental part or design applied thereto, the buttons in the present embodiment being of mother of pearl. These buttons, beside contributing to the 55 pleasing appearance of the clasp, also serve as finger-grips for convenience in manipulating the arms in attaching the clasp to a collar, and detaching it.

Means are provided for pressing the arms 12, around their pivots 13, toward the bar 10, so as to bring and hold the gripping means 17 in gripping position on the fabric. These means are conveniently a pair 70 of springs or spring parts 27, 27, and the bar 10 is conveniently made hollow, as indicated at 29, for receiving said springs or spring parts. The bar is conveniently 75 bent from sheet metal to U-form, the springs inserted, and the upstanding edges bent over to close the open space. The springs or spring parts 27 are conveniently 80 made of a strip 31, conveniently doubled on itself and conveniently having one end bent up and forming the blunt pin 19.

Moreover, the arms 12 are preferably provided with means, such as "flats" 36, on the ends 32 of said arms, coacting with said 85 springs 27 to hold said arms 12 in a position with their free ends separated from the bar 10 (position shown in Fig. 2).

The invention may receive other embodiments than those herein specifically illustrated and described.

What is claimed is:

A collar clasp comprising a bar, a pair of spring pressed arms hinged to said bar at their adjacent ends, and means on said bar 95 and arms for gripping fabric, said means comprising pins projecting from said bar, and ornaments at the ends of said arms, and a tubular intermediate portion between said ornaments and said arms, adapted to 100 be expanded against parts of said arms and of said ornaments to fasten said ornaments on said arms, said tubular intermediate portions, in the closed position of said arms, fitting over said pins, and constituting 105 sockets for said pins.

In witness whereof, I have hereunto signed my name.

HERMIE CLARENCE NEGGESMITH.
